UNITED STATES PATENT OFFICE

AXEL WASBERG, OF CHICAGO, ILLINOIS, ASSIGNOR TO CAMEL COMPANY, OF CHICAGO, ILLINOIS, A CORPORATION OF ILLINOIS

SEALING MEANS FOR CAR DOORS

Application filed March 26, 1930. Serial No. 438,985.

This invention relates to sealing means for car doors and it is an object of this invention to provide sealing means that will guide the door inwardly and outwardly during its vertical movements.

The invention comprises the novel structure and combination of parts hereinafter described and more particularly pointed out and defined in the appended claims.

10 In the accompanying drawing which illustrates a preferred form of this invention and in which similar reference numerals refer to similar features in the different views.

On the drawing:

15 Figure 1 is a side elevational of a car door and adjacent parts of the car involving this invention;

20 Figure 2 is an enlarged fragmentary sectional view taken thru the sealing and guiding means upon the line II—II of Figure 1; and

25 Figure 3 is a view similar to Figure 2 showing a modified form of sealing and guiding means.

As shown on the drawing:

Referring now to the drawing, the numeral 1 represents a sliding door which may be of any known construction and which is supported during its sliding movements upon a pair of spherical rolling elements 2 mounted in a retainer 3 which is supported for relative movement in a rockable housing 4 which has eccentric pivots 5 at its end which are journaled in bearings upon the 30 ends of the door. A handle 6 is attached to the housing 4 so that upon rocking the lever transversely to the door, the door will be elevated and supported upon the balls for rolling movement in a manner substantially 35 disclosed in the Fehr and Lute application Serial No. 393,914, filed September 20, 1929. The lower portion of the door will move inwardly and outwardly during its lowering and elevating movements.

40 The upper margin of the door is provided with a stiffening and metal guiding member 7 having an inwardly offset channel comprising a web 8 and an outwardly directed flange 9. The side plate 10 of the car is in 45 the form a Z bar having an attaching flange

10a, an outstanding horizontal web 10b and a depending flange 10c. A sealing and guiding member 11 of metal is attached to the web 10b of the Z bar and this member has a downwardly and inwardly inclined flange 55 12 terminating in a substantially horizontal lip 13 positioned below the aforementioned flange 9. The guide member 11 extends beyond the door opening preferably to a point where it will guide the door throughout its 60 opening movements.

In connection with this structure, it will be observed that the web 8 of the channel guide upon the door is limited in its inward movement by the depending flange 10c 65 of the side plate and is limited in its outward movement by the depending inclined flange 12 which also serves the purpose of forcing the door inwardly when the edge of the flange 9 engages therewith during the 70 lowering movements of the door from the dotted line position shown in Figures 2 and 3.

In Figure 3, a slight modification has been illustrated. In this instance, the guide 75 and sealing member 14 upon the side plate has a downwardly and inwardly inclined flange 15 and the stiffening guide and sealing member 16 upon the door is longitudinally bowed inwardly producing a substantially 80 V shaped member into the V portion of which the downwardly inclined flange 15 extends. In connection with this modified structure, it will be noted that the upper flange 17 of the sealing guide 16 on the 85 door is adapted to slide upon the downwardly inclined flange 15 of the sealing member 14 upon the side plate 10. It will also be noted that the guide members 7 and 16 cooperate with the depending flange 10c of 90 the Z-bar to exclude the weather and to prevent the door from frictionally engaging the car sheathing in its movements.

Accordingly, the upper margin of the 95 door is always sealed and is appropriately guided during its raising and lowering movements due to the fact that the sealing guide thereon is confined between the depending flange 10c of the side plate and the sealing member thereon. When the door is 100

lowered, the cooperation of the downwardly and inwardly inclined flange on the guide member which is attached to the side plate with the guide member on the door will 5 force the door inwardly until such latter guide member substantially abuts the flange 10c.

This depending flange 10c will also prevent the door from swinging inwardly during 10 operation and scraping the side of the car in addition to its cooperation with the sealing guides for the exclusion of weather.

I am aware that many changes may be made and numerous details of construction 15 may be varied through a wide range without departing from the principles of this invention, and I therefore do not purpose limiting the patent granted hereon otherwise than necessitated by the prior art.

20 I claim as my invention:

1. In a car having a side plate with a depending flange, a sealing guide upon said plate and having a downwardly and inwardly inclined flange spaced from said depending 25 flange in combination with a door having an upper sealing and guiding member located between said depending flange and first mentioned sealing member and cooperating with the former to exclude the weather 30 and to space the door from the car sheathing during its movements.

2. In a car having a side plate with a horizontal web and a depending flange, a guiding and sealing member attached to 35 said web and having a downwardly and inwardly inclined flange, in combination with a lift door having a sealing guide upon its upper margin extending between said downwardly inclined flange and said depending 40 flange and cooperating with said inclined flange for forcing the door inwardly until said sealing guide substantially abuts said depending flange for excluding the weather.

3. In a car having a side Z bar, a guiding 45 and sealing strip attached to the web of said Z bar, and having a downwardly and inwardly inclined flange, in combination with a door having a guide and sealing member with a flange engaging said downwardly 50 inclined flange and limited in its inward movement by a flange of said Z bar.

4. In a car having a side plate with a depending flange, a guiding and sealing member attached to said side plate, a door having 55 a sealing and guiding member extending between said depending flange and said first mentioned guiding and sealing member and cooperating therewith for guiding said door and excluding the weather.

60 5. In a house car having a side plate with a depending flange, a guiding and sealing member attached to said side plate and having a downwardly and inwardly inclined flange spaced from said depending flange, in 65 combination with a door having a metal

member projecting above said door and located between said guiding member and said depending flange, said metal member having an inwardly directed portion extending over the top of the door for cooperating with said depending flange to form a seal and to space the door from the car sheathing during its movements and terminating in an outwardly directed portion co-operating with said inwardly inclined flange on guiding sealing member.

6. In a house car having a side plate with a depending flange, a guiding and sealing strip attached to said plate and having a downwardly and inwardly inclined flange spaced from said depending flange to form a guideway, in combination with a door having a guiding and sealing member attached to the upper margin thereof and bent inwardly and outwardly and extending into 85 said guideway.

In testimony whereof I have hereunto subscribed my name at Chicago, Cook County, Illinois.
